UNITED STATES PATENT OFFICE.

KARL M. WISE, OF BIRMINGHAM, MICHIGAN, ASSIGNOR, BY MESNE ASSIGNMENTS, TO THE CLYMER MANUFACTURING COMPANY, OF DENVER, COLORADO, A CORPORATION OF COLORADO.

SPOTLIGHT.

Application filed April 7, 1921. Serial No. 459,456.

To all whom it may concern:

Be it known that I, KARL M. WISE, a citizen of the United States, and residing at Birmingham, in the county of Oakland and State of Michigan, have invented a new and Improved Spotlight, of which the following is a specification.

This invention relates to adjustable lamps adapted to project beams of light onto any 10 desired spot within a wide field, and its object is to provide a lamp of this character and its mounting which may be so attached to a screen, especially to the windshield of a motor vehicle or power boat, that the lamp 15 on the front side can be manipulated from the rear side of the screen.

A further object of this invention is to so construct the mounting that the lamp may be readily removed therefrom, and if provided with a cable of sufficient length, can be used as a trouble light.

Another object of this invention is to provide a simple and easily adjusted mounting which will not get out of order and which 25 will hold the lamp in any desired position.

In the accompanying drawing, Fig. 1 is a longitudinal section of the lamp mounting attached to a windshield and of part of the lamp, the remainder being in elevation. Fig. 2 is a longitudinal section of a connector. 30 Fig. 3 is an elevation of a slightly modified form of lamp. Figs. 4, 5 and 6 are central longitudinal sections of other forms of lamp mountings which may be substituted for 35 that shown in Fig. 1.

Similar reference characters refer to like parts throughout the several views.

While I have indicated a windshield pane 1 through a circular opening in which the 40 lamp embodying my invention is mounted, it will be understood that it is equally adapted to be mounted in any other desired shield or screen. The body 2 of the mounting is in the form of a sleeve which has a flange 3 between which and the flanged nut 4 the 45 screen may be gripped, the nut screwing onto the hub 5, which is formed with a seat 6 for the ball 7 providing a universal pivot. A bushing 8 forming a support and bearing 50 seat 9 for the ball 7 screws into the outer end of the mounting for disposal concentrically with the opening in the screen 1. Screwing this bushing in or out determines 55 the firmness with which the ball is held in the mounting. In the claims I may refer

to the assembly of the members 2, 4, and 8 as a housing, but since other constructions may be used, I do not desire to be limited to the peculiar type of housing shown and described.

A hollow handle member 11, preferably of insulating material, is mounted on the inner reduced end 12 of a supporting sleeve in any desired manner. The larger end 14 of this sleeve is pressed into the ball 7 and fits so 60 tightly that considerable force is required to separate them. A lamp body 15 has a collar 16 at its rear end which is secured to the sleeve in any desired manner, and the sleeve is preferably formed with the well known 65 bayonet slots 17 by means of which the light bulb 18 may be held in position. The usual lens 19 may be mounted on the body 15 in any desired manner.

It is to be understood that no claim is 70 made to the construction of the lamp or to the contact block 10 within the sleeve 14, the block preferably being a cylinder with parallel metal tubes 19 in which the conductor wires 20 which enter through the handle 75 may be secured by the screws 21. The contact posts 22 are held out by the springs 23 to engage the two terminals 24 of the base 25 of the light bulb. A two contact lamp 80 is shown because the lamp base cannot be 85 grounded through a glass screen but any electrician can vary the construction to suit it for a grounded mounting. The plug 10 may be secured in position by a screw 26.

In Fig. 3 I have shown a sleeve 27 instead 90 of the sleeve 14 of Fig. 1, and this sleeve 27 formed with a bend whose angle substantially may equal or exceed the angle through which the ball 7 may be swung so that the beam of light may be projected at right 95 angles to the screen or at substantially any angle between that line and a plane parallel to the screen, this being possible by reason of the ball being freely rotatable in the mounting. When the angle of the bend of 100 the sleeve 27 exceeds that through which the ball and sleeve 27 may be swung, it will be impossible to project a light ray at right angles from the windshield 1. This may be 105 desirable in such localities where the projection of rays of light "dead-ahead" of motor vehicles is forbidden.

In Fig. 1 I have shown a pin 29 extending 110 from the bushing 8 into a groove 30 in the ball 7. When the handle 11 is rotated

in either direction, the ball 7 and bushing 8 turn with it and so screw this bushing into or out of the body 2 and lock or unlock the ball 7 and the spot light. This is quite convenient as the lamp may be locked in any desired position from inside the vehicle.

Instead of a solid ball 7 I may use the construction shown in Fig. 6 wherein two shells 32 and 33 constitute a ball, either being slidable on the tube 12 and held away from the other by a spring 34. The spring will be tensioned by the bushing 8 and the spot light may be held as firmly as desired.

In Fig. 5 I have shown a structure which differs from that in Fig. 1 in that the body 35 of the mounting is bored sufficiently large to receive a spring 36 which presses the cupped washer 40 against the ball 7, the spring abutting against the split ring 38. The bushing 39 is held in position by means of pins 37 which enter well known bayonet slots 41 in the front end of the body 35. The initial tension of the spring 36 determines the firmness with which the spot light is held.

In the embodiment of my invention shown in Fig. 4, the tube 42 is independent of the sleeve 44 and the adjacent ends of the tube 42 and sleeve 44 are connected to the hollow hemispheres 43 and 45 respectively. These hemispheres are kept in position by the spherical band 46 and are held more or less firmly in this band by the spring 47. The band 46 is held firmly in the seat 48 in the mounting 49 by a bushing 50, also provided with a seat 51, and this bushing may be positioned by the pins 52 engaging in bayonet slots 53 in the front end of the mounting. These bayonet slots as well as those employed in the structure illustrated in Fig. 5 are not detailed because of their very common use in the arts.

In each case, a ball is adjustably seated in a mounting and while Figs. 1 and 3 show manually operable bushings to determine the firmness of the grip of the mounting on the ball, Figs. 5 and 6 show springs for this purpose. Fig. 4 shows two sets of sliding surfaces of which the grip of one is determined by a spring and of the other by a bushing.

The details of construction and the proportions of the parts may all be varied by those skilled in the art without departing from the spirit of my invention as set forth in the following claims.

I claim:—

1. In an adjustable lamp, a spherical body adapted to extend through a hole in a screen, a sleeve and a cooperative member for securing the body in position in the screen, means for retaining the body in said sleeve, a conduit through said body, a handle and a lamp cooperatively connected to opposite ends of said conduit, and means connecting the body

and said body retaining means whereby rotation of the body will turn said body retaining means to lock the body and lamp in position.

2. In an adjustable lamp, a spherical body adapted to be positioned within an opening in a screen, a sleeve and a cooperative member for securing said body in position in said screen, means for removably retaining the body in said sleeve, a conduit extending through and projecting beyond said body, a handle and a lamp cooperatively connected to opposite ends of said conduit, and means connecting the body and said body retaining means comprising a circumferential groove in the body and a pin carried by said body retaining means and extending into said groove, whereby rotation of the body will turn said body retaining means to lock the body and lamp in position.

3. A spotlight comprising, a housing adapted to be mounted in a windshield, a lamp supporting member extending through and supported by the housing for substantially universal angular movement with respect to the windshield, a handle carried by one end of said member, a lamp, and means including a stem connecting said lamp and the other end of said member, for supporting said lamp in connection with said member so that the lamp may be oscillated, by movement of said handle, within a limited range about an axis normal to the axis of said member and may be rotated about the axis of said member to increase the range thereof.

4. A spotlight comprising, a housing adapted to be mounted in a windshield, a lamp supporting member extending through the housing, a handle on one end of said member, a lamp on the opposite end of said member, said lamp arranged at an angle so that the axis of the shaft of light directed by said lamp will always be disposed at an angle to the axis of said handle, and means for mounting said member within said housing whereby said handle may be swung about a pivot point formed by the intersection of a plane parallel to the windshield and the axis of said housing to swing the lamp for a relatively limited light directing range, and whereby the handle may be rotated about the axis of the handle to rotate the lamp for directing the light shaft over a relatively greater range.

5. In combination with a vehicle windshield having an opening therethrough, a bearing for a light supporting member mounted adjacent the opening concentrically with respect thereto, a light supporting member passing through the opening and connected with the bearing for movement on axes transverse to the axis of the bearing, and a spotlight on one side of the windshield and connected with one end of the said member

so that the center of the light will be offset with respect to the pivot center formed by the intersection of said axes in any position into which the said member may be moved, 5 said end of the member being adapted to assume a position in a plane substantially parallel with the face of the windshield, the other end of the said member being provided with a handle on the other side of the 10 windshield.

6. A windshield spotlight comprising, a housing adapted to be secured to a windshield through an opening therein, a spotlight, a handle, supporting means for said

handle and spotlight including a universal 15 pivot within said housing, said handle being disposed at one side of said housing and said spotlight at the other, said spotlight supporting means and spotlight being so relatively disposed that upon swinging said 20 handle the spotlight may be correspondingly swung in paths the limits of which form a path eccentric to an axis of said pivot perpendicular to the windshield, and so that rotation of said handle will rotate the spotlight to describe a path concentric with the 25 axis of the handle.

KARL M. WISE.
